UNITED STATES PATENT OFFICE.

CHARLES H. WOOD, OF OAKLAND, CALIFORNIA.

WINDOW-SHADE FIXTURE.

Application filed July 30, 1923. Serial No. 654,628.

My invention is an improved shade mounting particularly applicable to enclosed automobiles, but may also be applied to the usual type of double hung windows. 5 The object of my invention is to provide a mounting of simple and inexpensive construction, and which may be readily applied or removed from the window.

With the present method of hanging a curtain, it is soon torn by the action of the wind coming through the window. My mounting entirely obviates this difficulty, since it is secured to the top of the window and raises or lowers with it.

Other objects and advantages will be more specifically pointed out and described in the following detailed description.

In the annexed drawing in which my invention is illustrated:

20 Figure 1 is a side view of my mounting positioned on the door of a closed automobile.

Figure 2 is a sectional view taken on the line 2—2 of Figure 1.

25 Figure 3 is a side view of my mounting.

Figure 4 is an end view of the same.

Referring more particularly to the drawing, my shade mounting comprises a channeled clamping member 1, which is adapted to rest upon the top of the window 2, as shown in Figures 1 and 2. Brackets 3 and 4 are secured to the ends of the member 1 in which the shade 5 is mounted. When my mounting is used upon the doors of an automobile, the brackets 3 and 4 are positioned below the top of the member 1 to permit the glass and the top of said member to enter the top recess in the door.

To further lighten my mounting the

member 1 is cut away in the center, sufficient metal being retained to properly grip the window and provide a rigid mounting. The member 1 is preferably formed of a single piece of material which is cut and then bent into shape. It will be seen that the window may be raised or lowered any desired distance, and the shade adjusted to keep out the sun without any danger of the shade being torn by the wind.

It is obvious that the brackets 3 and 4 50 may be used to support a bar from which to drape a curtain instead of hanging a shade. It is also obvious that the central part of the channeled member 1 may be omitted, in which case the brackets would be 55 secured to a short channel for each bracket.

Having described my invention, I claim:

1. In combination, a window frame, a window pane slidable therein and set back from the front face thereof, a strip of material bent into U shape in cross section straddling the upper edge of the pane, brackets extending in parallel relation from one outer face of the strip at opposite ends thereof, and a shade supported in the brackets in immediate proximity to the pane, the shade being confined between the face of the pane and the front plane of the frame. 60

2. A combination as defined in claim 1 in which the U shaped strip is coextensive with 65 the width of the window pane and is made to fit against the edges of a groove formed in the frame above the pane for effecting a tight closure when the pane is pushed upwardly. 70

In testimony whereof I affix my signature.

CHARLES H. WOOD.
